UNITED STATES PATENT OFFICE.

JOHN TREMPER, OF BUFFALO, NEW YORK.

IMPROVEMENT IN VARIABLE CUT-OFF GEARS FOR STEAM-ENGINES.

Specification forming part of Letters Patent No. 37,062, dated December 2, 1862.

To all whom it may concern:

Be it known that I, JOHN TREMPER, of Buffalo, in the county of Erie and State of New York, have invented a new and Improved Variable Cut-Off Gear for Steam Engines; and I do hereby declare that the following is a full, clear, and exact description of the same, reference being had to the accompanying drawings, forming part of this specification, in which—

Figure 1 is a front view of the cut-off gear and the shell which contains the cut-off valve. Fig. 2 is a side view of the cut-off gear, omitting such parts of the framing as would conceal the working parts. Fig. 3 is a front view illustrating the addition of a device for continuing the operation beyond half-stroke. Fig. 4 is a plan, on a larger scale, of some of the details of the addition shown in Fig. 3. Fig. 5 is an end view of the same.

Similar letters of reference indicate corresponding parts in the several figures.

This invention consists in a certain novel mechanism composed of two toothed lifters or tripping-levers jointed to two arms of a rock-shaft, and operating in combination with a toothed block on the upright stem or rod of the cut-off valve, and with a cone or wedge connected with a governor or otherwise made adjustable, whereby I obtain a gradual opening of the cut-off valve for the admission of steam to the engine-cylinder, and a sudden closing of the same to cut off the steam at such point as may be required during the first half of the stroke of the piston; and it also consists in certain means applied in combination with the aforesaid tripping-levers for the purpose of enabling the steam to be continued on the piston to different points beyond half-stroke.

To enable others skilled in the art to make and use my invention, I will proceed to describe it with reference to the drawings.

A is the shell, which contains the cut-off valve. This valve may be of any known kind, though I prefer to use one that is perfectly balanced when exposed to the action of the steam.

a is the rod by which the valve is operated, constituting in the example represented the stem of the valve; but it may be connected with the valve in any suitable manner to open

the valve by its upward movement, the said rod working through a suitable fixed guide, b, which keeps it upright, and having applied to it between the said guide and a collar, c, on its lower part, a spring, d, which exerts a constant downward pressure, and thereby tends to close the valve. On the upper part of the said rod there is firmly secured a lifting-block, B, on opposite sides of which there are two teeth, e e, which are acted upon by the tripping-levers to open the valve, and on another side of which there is formed a tongue, f, working between guides g g, to prevent the rod from turning.

D is the rock-shaft by which the opening movement of the valve is effected, arranged horizontally in a bearing in a frame, M, erected upon the shell A, with its axis in the same plane with the axis of the valve-rod a. This rock-shaft has fast upon it at the end farthest from the valve-rod an arm, h, by which the connection is made with the eccentric on the main shaft of the engine, and it has also fast upon it at the end next the valve-rod two arms, E E', to which are attached the lifters or tripping-levers F F', which operate upon the teeth e e' to lift the rod and open the valve. The arms E E' have a downward inclination from each other and from the rock-shaft at an angle from ninety degrees to one hundred and twenty degrees, or thereabout. The tripping-levers F F' are attached by their lower ends by pivots i i' to the ends of the arms E E', and are arranged on the two opposite sides of the valve-rod on which the teeth e e' of the lifting-block B are situated, and each has formed upon its inner side a tooth, j or j', to engage with the tooth e or e' on the corresponding side of the lifting-block, and the parts of the inner sides of the said levers above their tee-h j j' have backward and upward inclination, to correspond with the profile of the cone G, which may be either attached to the governor in such manner as to be thereby depressed when the speed of the engine increases, and vice versa, for the purpose of governing the engine by the variation of the point of cutting off steam, or may be adjusted by any other means to cause the cutting off of the steam at any fixed point in the first half of the stroke of the engine-piston. This cone, when used in connection with a

governor, may be arranged to turn freely on the lower part of the upright rod *k*, which connects it with the governor, or through which the governor operates to raise and lower it. Whichever way the said cone may be turned, it is in condition for operating on the tripping-levers, and in this respect it is superior to a simple wedge, which would require some contrivance to prevent it from turning and keep its edges opposite to the tripping-levers. The two tripping-levers are connected by a spring, *l*, which acts to prevent them from falling or slipping backward. The rocking motion of the arms *E E'*, produced by the oscillating motion of the rock-shaft derived from the main shaft of the engine, causes the tripping-levers each to rise and fall once during each revolution of the engine, and each one, by the action of its tooth *j* or *j'*, upon the corresponding tooth *e* or *e'* of the lifting-block, lifts and opens the cut-off valve at the proper time for the induction of steam to the cylinder. As each tripping-lever rises, if the cone *G* is in a sufficiently-low position the inclined inner surface of the part of the said lever above its tooth *j* or *j'* comes in contact with and slides up the cone, and as it continues to rise it is forced outward by the wedge-like action of the cone until its tooth escapes from the corresponding tooth of the lifting-block and permits the valve to be closed suddenly by the spring and the steam to be thereby cut off. This escape of the tooth of the tripping-lever from the tooth of the lifting-block takes place at an earlier or later point in the stroke of the engine-piston, according as the cone is more or less depressed, and hence when the speed of the engine begins to increase and the cone is thereby caused to be depressed, the escape of the tripping-lever takes place at an earlier point in the stroke, and when the speed is diminished and the cone allowed or caused to rise the escape of the tripping-lever takes place later, and in this way the cut-off is made to regulate the speed of the engine. In the downward movement of the tripping-pieces with the arms *E E'* they are gradually drawn toward the lifting-block by the spring *l* as fast as permitted by the cone, and their teeth slip over and pass under the teeth of the lifting-block ready for a new lift.

By the arrangement of the arms *E E'* at such an angle to each other below the rock-shaft, as hereinbefore described, their operation is caused to be within the lower half of a circle, and the highest position to which they rise is not above a horizontal one, and hence their movement is at first very slow and gradually faster, and they are thereby caused to open the valve with a very slow movement, corresponding nearly with that of the engine-piston at the commencement of its stroke, and as the piston is moving faster the valve opens quicker to produce a desirable progressive increase in the supply of steam to the cylinder. In order to stop the cut-off when closed without violent concussion, the upper part of the guide *b* is

hollowed out concentric with the rod *a* in the form of a cup, and has applied within the cup-like cavity a ring or rings, *n*, of vulcanized india-rubber, cork, or other elastic material, to form a cushion, and the bottom of the lifting-block *B* is made of a form to enter the said cup, and so arranged or of such depth that it will come in contact with the cushion *n* when the valve in its descent arrives in a closed condition. The lifting-block is thus made to serve the additional purpose of a stop to the valve. As the liberation of the valve by the action of the cone on the tripping-levers cannot be effected at any point in the stroke of the piston beyond half-stroke, I propose to use in connection with them, in engines in which it is desirable to cut off beyond half-stroke, the contrivance shown in Figs. 3, 4, and 5. In those figures *N* is a short bar secured firmly to one side of the frame *M*, and projecting horizontally therefrom toward the rod *a* and tripping-levers *F F'* in a direction perpendicular to the planes of oscillation of the said levers. This bar is slotted horizontally, for the reception of portions of two slides, *P P'*, which are fitted to it in such manner as to be capable of sliding toward and from the sides of the tripping-levers, and these slides are connected rigidly together by a short transverse pin, *p*, which crosses the central vertical slot, *r*, of the bar *N*. This slot receives within it a plate, *Q*, (see Fig. 3,) which is suspended vertically from a suitable connection with the governor in such manner as to move up and down with the cone *G*. This plate contains a vertical slot, *s*, which is fitted to a fixed pin, *t*, secured across the slot *r* of the bar *N*, and the said plate also contains an oblique slot, *s'*, which fits to the pin *p*, and as the said plate is caused to move upward and downward with or by the governor the slot *s* and pin *t* keep it vertical, and the faces of the oblique slot *s'* act as wedges upon the pin *p*, and cause it to move the slides *P P'* from and toward the tripping-levers, one of them being arranged opposite to each of said levers. To the two slides there are attached by pins *u u* two laterally-swinging toes, *R R'*, one to each slide. These toes have applied to them springs *v v'*, which tend to press them toward each other and hold them within grooves provided in slides for their reception; but portions of the said toes project beyond the ends of the slides toward the tripping-levers, and these portions are beveled on their inner sides, as shown at *w w* in Fig. 5, and on their outer sides, as shown at *x x* in same figure, the bevel on the outer side being oblique, both in a direction lateral and longitudinal to the said toes, and making the upper sides, *y y*, of the taper form shown in Fig. 1. These upper sides are also slightly beveled, to give them a downward inclination toward the outer side, as shown in Fig. 5. In each one of the tripping-levers there is secured a pin, *6*, which operates in the following manner, in combination with the toes *R R'*: The valve-rod is brought down by the spring *d* to such

a position as to bring the pins 6 6 below the toes, and when the tripping-levers are not thrown out by the cone before the ascent of the said levers is completed, the pins are brought to position above the toes. In moving upward the said pins work in contact with the inner beveled faces, *w w*, of the toes and push them aside; and, when the said pins rise above the toes the latter spring back again into or toward the slides *P P'*, and the pins have to descend outside of the toes, and in such descent they are pressed outward in such manner as to throw aside the tripping-levers from the lifting-block and liberate the valve. It has been before stated that the plate *Q* moves up and down with the cone *G*, and in that moving up and down it moves the slides *P P'* and their attached toes *R R'* longitudinally toward and from the tripping-levers, and the lower it is depressed by the governor the farther the toes will be pushed toward the tripping-levers and under the pins 6 6. When the toes are presented far under the pins, as is the case when the plate *Q* and cone *G* are depressed nearly far enough to make the latter throw off the tripping-levers, the pins, in being brought down into contact with the wide portion of the upper inclined surfaces, *y y*, of the toes, are caused to slip quickly across the said surfaces and drop over the outside of the toes, and so made to throw the tripping-levers from under the lifting-block almost as soon as the descent of the tripping-levers commences, and hence permit the valve to remain open very little longer than if the tripping-levers had been thrown out by the cone; but when the toes are presented a less distance under the pins, as is

the case when the plate *Q* and cone *G* are not so much depressed, the pins descend on the narrower portions of the surfaces *y y*, and, though they slip quickly across those portions of the surfaces, they are caught by the surfaces *z z*, down which they pass more gradually, and by which they are caused to draw the tripping-levers more gradually from under the lifting-block, and so keep the valve open during a longer portion of the stroke.

What I claim as my invention, and desire to secure by Letters Patent, is—

1. The attachment of the lifters or tripping-levers *F F'* by pivot-joints to two arms, *E E'*, which are so arranged upon a rock-shaft or its equivalent as to work below the axis thereof, and so cause the opening of the valve slowly at first and with a gradually-increasing velocity, substantially as and for the purpose herein specified.

2. The combination of the lifters or tripping-levers *F F'*, applied as above specified, the lifting-block *B*, and the cone *G*, substantially as and for the purpose herein set forth.

3. The arrangement of the lifters or tripping-levers *F F'* and the toothed lifting-block *B*, in combination with the rock-shaft *D* and a cone, *G*, connected with the governor or otherwise controlled, substantially as herein specified.

4. The mechanism shown in Figs. 3, 4, and 5, and herein described, for tripping the levers *F F'* in their downward motion, substantially as and for the purpose herein set forth.

JOHN TREMPER.
